UNITED STATES PATENT OFFICE.

IRVING TIGER, OF FERNDALE, NEW YORK.

DESIGN FOR A DINING-TABLE FIXTURE.

48,876.

Specification for Design.

Patented Apr. 11, 1916.

Application filed November 24, 1915. Serial No. 63,817. Term of patent 14 years.

To all whom it may concern:

Be it known that I, IRVING TIGER, a citizen of the United States, residing at Ferndale, in the county of Sullivan and State of New York, have invented a new, original, and ornamental Design for a Dining-Table Fixture, of which the following is a specification, reference being had to the accompanying drawing, forming part thereof.

The figure is a perspective view of a dining table fixture showing my new design.

My design for a dining table fixture presents a circular base from which a vase-like holder rises centrally, together with a series

of smaller auxiliary holders rising from lateral arms and terminating short of the top of the central holder, the said arms having each a loop therein, there being on the arms outwardly disposed horizontal opposed semi-circular members.

I claim:

The ornamental design for a dining table fixture, as shown and described.

IRVING TIGER.
